Primary Examiner — Paul D Bohannon**CLAIM**

I claim the ornamental design for a seating unit, as shown and described.

DESCRIPTION

FIG. 1 is a front perspective view of a seating unit showing my design;

FIG. 2 is a rear perspective view of the seating unit of FIG. 1;

FIG. 3 is a front view of the seating unit of FIG. 1;

FIG. 4 is a rear view of the seating unit of FIG. 1;

FIG. 5 is a right-side view of the seating unit of FIG. 1;

FIG. 6 is a left-side view of the seating unit of FIG. 1;

FIG. 7 is a top view of the seating unit of FIG. 1; and,

FIG. 8 is a bottom view of the seating unit of FIG. 1.

The broken lines shown in the drawings illustrate portions of the article that form no part of the claimed design.
